TAMPERPROOF SCREW CLOSURE

Donald L. Spender, Waterbury, Conn., assignor
to Scovill Manufacturing Company, Waterbury,
Conn., a corporation of Connecticut

Application December 6, 1945, Serial No. 633,099

3 Claims. (Cl. 220—39)

1

This invention relates to tamper-proof containers and particularly to one that will have a visible indication as to whether or not the interior of the container may have been tampered with in being shipped from one destination to another.

One of the objects of this invention is to provide a container and a cover having mutually threaded engagement, and wherein a locking means is devised after the cover has been assembled into position for sealing the container for shipping and which will necessitate the breaking of the locking means in order that the contents of the container may be removed.

A further object is to provide a container and cover member having threaded interengagement with each other and wherein the locking means is so constructed as to give a visible indication that the cover may have been removed before having reached its final destination, giving proof that the contents may have been fraudulently interfered with.

A further object is to provide a container and cap of the above construction wherein one or more lugs are provided in the skirt of the cap adjacent its open end, and initially lying in the plane of the skirt, and designed to be biased inwardly therefrom to engage permanently in a circumferential exterior recess in the container as a means for locking the two parts together.

In making closure containers of the above character, even though the metal may be of a relatively soft character, such as aluminum or light tempered brass, and where lugs are provided in the side walls of one of the members, there is always the inherent tendency for the lugs to spring back toward their initial position when being biased therefrom, and it is one of the objects of my invention to provide a construction wherein it can be assured that the lugs, that are to be bent after the assembly of the cap to the container to effect the locking seal, will be disposed in a set position without danger of springing back and lessening the locking effect.

With these objects in view and others not specifically referred to, the invention consists in the features, combination, details of construction and arrangements of parts which will first be described in connection with the accompanying drawings and then more particularly pointed out.

Fig. 1 is a side elevational view of my container and cap shown in an assembled state.

Fig. 2 is a sectional view through the cap and the upper end of the container showing them as they appear in a separated state in a view taken substantially at right angles to the view of Fig. 1.

2

Fig. 3 is a similar sectional view showing the upper end of the container and the cover as they appear in assembled state, the view being taken along the line 3—3 of Fig. 1.

Fig. 4 is an enlarged elevational view of the cap member showing particularly one of the locking lug elements, and

Fig. 5 is a view showing three fragmentary sections of the cover member illustrating the various stages of the formation of the locking lug.

Referring now to the drawing wherein like numerals denote corresponding parts throughout the several views, the numeral 10 indicates generally a cylindrical container having the usual 15 closed base-end and an open upper end, the latter adapted to be sealed by a screw cap 11. Specifically the cylindrical container has a rolled threaded portion 12 adjacent its upper open end, and the cap 11 is provided with a complementary 20 thread 13 formed in its depending wall 14. The unthreaded portion of the cap 11 below the threads, as appearing in Fig. 2, provides for a cylindrical skirt 15 from which is cut a pair of 25 diametrically opposed locking lugs 16. As best shown in Fig. 4, this locking lug 16 is spaced from the surrounding wall structure on three sides by an inverted U-shaped clearance slot 17 to assure that the lug will be free of the surrounding skirt member for ease in deforming the lug out of its 30 normal position as will appear later. The lugs 16 are integrally attached to the main body of the skirt 15 by bridge members 18 and 19 which are relatively narrow portions of metal strips adjacent the open end of the cap 11.

35 In order to provide means in the container 10 for effecting a locking connection between the cap 11 and the container 10, a circumferentially inwardly formed recess 20 is provided in the upper end of the container immediately below the 40 threaded portion 12. The construction of the recess 20 is such as to provide a relatively sharp shoulder 21 adjacent its upper end and a more or less tapering shoulder 22 adjacent its lower end.

When the container has been filled with the 45 material or article to be shipped, as for example a vial of liquid, this construction is used to assure a tamper-proof locking seal. After placing the contents in the container 10, the screw cap 11 can be threadedly assembled in the usual manner until a sealing gasket 23 disposed in the 50 upper closed end of the cap 11 is seated against the upper edge of the container 10 as best shown in Fig. 3. The locking lugs 16 previously mentioned are initially disposed in the circumferential plane of the skirt 15 and with the cap fully 55

assembled, the position of these lugs 16 is such as to line up with the recess 20 of the container whereupon the lugs 16 may be forced or biased inwardly by any suitable instrument such as a screw driver blade 24 or any other similar instrument wherein the upper edges 25 of the lugs are disposed in close proximity to the sharp shoulder 21.

While the containers that are used for the purpose, for which the containers of this particular art are employed, are made of a somewhat soft metal, such as aluminum or relatively soft brass, I have found that there always has been sufficient resiliency in the metal so that there is a tendency for lugs of the character here disclosed to spring back toward their normal position after once being forced manually inwardly as in the manner indicated in Fig. 3 so that the full locking effect of the lugs may not be attained. In order to assure that the locking lugs can be set into a permanent locking position without danger of springing back toward their initial state, I have found that by putting in a preliminary forming operation at the point where the lugs are bent relative to the cap skirt, the subsequent forming of the lugs 16 to their final interlocked position in the recess of the container can be assured. To show how this is accomplished, reference is made particularly to Fig. 5 and first to the left hand view wherein the lug 16 is initially disposed in the circumferential plane of the skirt 15 throughout its entire length, and it should be understood that that is the position that the lugs 16 assume before the assembly of the cap 11 to the container 10. Without disturbing the main body portion of the lug 16, I deform outwardly a small portion of the lower end of the lug as at 16' with the twist occurring particularly in the area of the bridge members 18 and 19, this forming being of an angle substantially equal to what the main body of the lug 16 is later to assume when in the locking position. This preliminary forming is best shown in the middle view of Fig. 5. After the cap 11 is completely assembled, as shown in Fig. 3, the lug is then finally formed inwardly by the instrument 24, such as a screw driver blade or similar instrument, to be received into the recess 20, its final locking position being shown in the right hand view of Fig. 5. By this particular construction in biasing the lug 16, as shown in the middle view of Fig. 5, to the right hand view of Fig. 5 there is no danger of the lug springing back to its initial position and disengaging partially from correct locking relationship with the recess 20 and lessening the locking connection between cap and container.

When it is desired, however, for the authorized person to have access to the contents of the container, it is necessary for such person to remove the cover by an unthreading operation and in so doing the lugs 16 will be forced out from their biased locked position in an axial direction and will break one of the weakened bridge members 18 or 19 or both and consequently will break the locking effect of the lugs 16. If there appears to be any disturbance of the lugs from their locked position such as a broken bridge, before the container may have reached its destination, it gives clear evidence that the cap may have been removed and the contents of the container tampered with by some unauthorized person.

As a further precautionary measure to assure that some persons with considerable skill might

not use a sharp instrument to force the lugs 16 out of the recess 20 in order to remove the cap without any visible indication that the cap has been removed by a broken or disturbed lug,

5 I have provided a circumferential projecting rib 30 of some width immediately below the recess 20. This rib is close enough to the lower edge of the screw cap 11 when assembled so that it will prevent any sharp instrument being inserted underneath the lugs 16 for reasons as above set forth.

10 While it will be apparent that the illustrated embodiment of my invention herewith disclosed is well suited to adequately fulfill the objects and 15 advantages primarily stated, it is to be understood that the invention is susceptible to variation, modification and changes within the spirit and scope of the following claims.

I claim:

20 1. A tamper-proof closure member comprising a container having a cylindrical open end with a threaded section adjacent said open end, a continuous circumferential recess disposed in the outer wall of said container immediately below the threaded section, a threaded cap member for closing the open end of the container and having a cylindrical skirt section extending beyond its threaded section, and axial locking lug means formed in the skirt section of said cap 25 and initially lying in the plane of said skirt, said lug means having an inverted U-shaped clearance slot circumscribing three of its sides and being connected to said skirt by frangible bridging members adjacent the lower end of said skirt, 30 said cap member being of relatively inert material such that after assembly to the container said lug means may be manually bent inwardly from its initial position to lie within the area of said container recess at any position that the cap 35 may be threaded to for complete assembly upon said container.

2. A tamper-proof closure member comprising a container having a cylindrical open end with a threaded section adjacent said open end, 45 a continuous circumferential recess disposed in the outer wall of said container immediately below the threaded section, a threaded cap member for closing the open end of the container and having a cylindrical skirt section extending beyond its threaded section, axial locking lug means formed in the skirt section of said cap and initially lying in the plane of said skirt, said lug means having an inverted U-shaped clearance slot circumscribing three of its sides 50 and being connected to said skirt by frangible bridging members adjacent the lower end of said skirt, that portion of said skirt below said lug means and between the connecting bridge members being bent outwardly from the skirt 55 wall and at an angle to the initial position of said lug means, and said lug means upon the complete assembly of said cap to said container being bent inwardly to lie within the area of said container recess.

60 3. In a cap member for use on a tamper-proof container and having mutually threaded engagement therewith, said cap member having a cylindrical skirt below its threaded section and terminating the open end of said cap, axial lug means provided in said skirt and connected thereto by rupturable bridge members adjacent the lower edge of said skirt, said lug means normally lying in the plane of said skirt and designed to be later biased inwardly therefrom into locking engagement with said container, that

portion of said skirt below said lug means between said bridge members being initially formed outwardly of the plane of said skirt to an angular position substantially equal to that which the lug means is to assume when biased into locking position, said outwardly formed portion of the skirt below said lug means effecting a twist in the area of said bridge members to facilitate the rupturing of the same upon removal of the cap from a container.

10 DONALD L. SPENDER.
